APPOINTMENT SIGN FOR A BEAUTY SALON

David Rose, Flushing, N.Y., assignor to The Glembay
Company, Inc., New York, N.Y.

Filed Dec. 6, 1971, Ser. No. 205,481

Term of patent 14 years

Int. Cl. D20—03

U.S. Cl. D96—12 R

FIG. 1

FIG. 2

FIG. 3

FIG. 4

FIG. 5

FIG. 6

FIG. 1 is a front view of the appointment sign for a beauty salon showing my new design;

FIG. 2 is a top view of the appointment sign for a beauty salon;

FIG. 3 is a right side view of the appointment sign for a beauty salon;

FIG. 4 is a rear view of the appointment sign for a beauty salon;

FIG. 5 is a bottom view of the appointment sign for a beauty salon;

FIG. 6 is a sectional view of FIG. 1 taken between lines 6-6 for the appointment sign for a beauty salon.

The left side of the appointment sign for a beauty salon is the same as the right side view thereof. The top and bottom panels shown in FIGS. 1, 4 and 6 are transparent. The writing appearing on the top and intermediate panels in FIG. 1 is on the front side thereof as shown in the sectional view of FIG. 6.

I claim:

The ornamental design for an appointment sign for a beauty salon, as shown and described.
